UNITED STATES PATENT OFFICE

2,235,066

SHOE HOLDER

George F. Frazee, University City, Mo.

Application February 17, 1939, Serial No. 256,835

1 Claim. (Cl. 12—128.1)

The present invention relates generally to supporting devices, and more particularly to a device adapted to be removably anchored to a foundation for supporting footwear for shining, or for other operations.

An object of the present invention is to provide a device for supporting footwear in a position to be shined, or to be otherwise worked on.

Another object is to provide a device for maintaining footwear in a position for shining, or the like, which is adapted to automatically adjust itself to a particular shoe, or the like, for retaining the same in a position to be worked on.

Another object is to provide a device for supporting footwear in a position to be shined, or the like, which is removably supported by a foundation.

Another object is to provide a device for supporting footwear in a position to be shined, or the like, which includes a stationary member and a pivoted member biased into spread relation.

Another object is to provide a device for supporting footwear in a position to be shined, or the like, which is simple in construction, economical to manufacture, and adapted to fulfill all of the objects and advantages sought therefor.

Other objects and advantages will be apparent from the following description, taken in conjunction with the accompanying drawing, in which:

Fig. 1 is a plan view of a device constructed in accordance with the teachings of the present invention, the device being shown mounted on a vertical wall;

Fig. 2 is a side view of the device shown in Fig. 1, the footwear-receiving members being disposed in spread relation;

Fig. 3 is a side elevation of the device shown in Fig. 1, the footwear-receiving members being disposed in a closed relation and receiving a shoe; and,

Fig. 4 is a longitudinal cross-section through the device shown in Fig. 1.

Referring to the drawing more particularly by reference numerals, 10 indicates generally a footwear holder constructed in accordance with the concepts of the present invention. The footwear holder 10 comprises a shoe-receiving body 11 and a supporting block 12.

The shoe-receiving body 11 includes a horizontal bridging member 13 having a reduced extension 14 (Fig. 1). The member 13 has an enlarged portion 15 at the end remote from the reduced extension 14 which is cut away to pro-

vide a niche formed by a horizontal surface 16 and a vertical surface 17.

A heel member 19 is connected to the extension 14 by means of bifurcations 20 which embrace the extension 14. A pin 21 extends through suitable openings in the bifurcations 20 and the extension 14 and secures the heel member 19 to the horizontal member 13, shoulders 22 (Fig. 1) formed at the juncture of the extension 14 and the main portion of the horizontal member 13 contacting the edges of the bifurcations 20 to maintain the heel member 19 and the horizontal member 13 in fixed relation. The heel member 19 is convex at 23 to conform to the concave interior of the heel of a shoe, and includes a depression 24 to receive the top line of a shoe which is normally drawn inwardly to conform to the ankle of a wearer (Fig. 3).

A toe member 26 is pivoted to the extension 14 by means of a pin 27, which extends through suitable aligned openings in the extension 14 and in bifurcations 28. The toe member 26 includes a connecting element 29 and a toe element 30, which are secured in right-angular disposition by means of a pin 31 which extends through an opening 32 in the connecting member 29 and into a recess 33 in the toe element 30. The toe element 30 includes bifurcations 34, which extend around that end of the connecting element 29 remote from the pivot pin 27.

A heavy flat spring 36 is secured at one end between that portion of the heel member 19 between the bifurcations 20 and the lower side of the extension 14. The lower side of the extension 14 includes an elongated shallow recess 38 and a short deeper recess 39, the former of which receives the flat end of the spring 36 and the latter of which receives a flange 37 to prevent removal of the spring 36. The normal disposition of the spring 36 is as shown in Fig. 2.

The supporting block 12 is of the configuration clearly shown by Figs. 1 and 2. Converging openings 40 and an opening 41 receive screws 42 and 43, respectively, which extend into a wall 44. An angularly disposed recess 45 removably receives an angularly disposed pin 46 secured in a suitable opening in the horizontal member 13, the top and front face of the block 12 abutting the horizontal surface 16 and the vertical surface 17, respectively.

In use, the supporting block 12 is secured to some foundation, such as the wall 44. The shoe-receiving body 11 is secured to the supporting block 12 by inserting the pin 46 into the recess 45. The shoe holder 10 is then ready for use.

When it is desired to polish a shoe, or the like, the toe member 26 is pivoted about the pin 27 against the force of the spring 36 until the spring 36 is contiguous with the heel member 19. A shoe 47 is disposed about the toe element 30 and the convex portion 23 of the heel member 19. The toe member 26 is released, whereupon the spring 36 forces the toe member 26 into engagement with the toe and vamp portion of the shoe 10 47, which draws the heel of the shoe 47 against the convex portion 23 of the heel member 19 (Fig. 3). The shoe 47 is thus securely maintained in the relation shown in Fig. 3 by the spring 36 and can be readily shined, or otherwise worked 15 upon. To remove the shoe 47, it is but necessary to again force the toe member 26, the spring 36, and the heel member 19 into contiguous relation, whereupon the shoe 47 can be easily cleared.

It is evident that there has been provided a 20 simple and sturdy shoe holder which is adapted to securely maintain a shoe, or the like, in a position to be shined, or to be otherwise worked on. Manifestly, the shoe holder 10 achieves all of the objects and advantages sought therefor.

It is to be understood that the foregoing description and accompanying drawing are given for purposes of illustration and example, and not for purposes of limitation, the invention being limited only by the claim which follows. 5

What is claimed is:

A shoe holder comprising a supporting block and a shoe-supporting body, said shoe-supporting body including a horizontally disposed member removably connected to the block, said horizontally disposed member having the end remote from the block reduced to provide oppositely disposed shoulders, a heel member fixed to the reduced end of the horizontally disposed member by a single pin, said heel member having a bifurcated end embracing a portion of the reduced portion of the horizontally disposed member and abutting the said shoulders, a toe member pivotally connected to said horizontally disposed member, and a heavy flat spring connected to said heel member and yieldingly maintaining said toe member in divergent relation to said heel member. 10 15
